DISPLAY CASE STRUCTURE

Samuel Bloomfield, Chicago, Ill.

Application November 25, 1938, Serial No. 242,174

4 Claims. (Cl. 312—114)

A principal object of the present invention is the provision of an improved display case structure of a type having a frame with glass side walls, the frame being adapted for mounting 5 either flush or in raised position on a surface such as a counter or the like.

Another important object is the provision in a show case or display case structure of glass side panels each having a beaded or bulb edge and so 10 mounted in a casting frame that the beaded or bulb edge of one panel will overlie the edge of an adjoining panel to protect the latter edge, the beaded edges themselves providing protection against chipping and similar injury.

15 A further object is the provision in a device of the class described of a frame structure defining a case with open sides and grooves at the margins of said slides, there being glass side wall panels fitted into said grooves in the particular manner 20 hereinafter specified.

A still further object is the provision of sealing 25 means for glass panels fitted into grooves in a frame structure, said sealing means including a fabric or shock-absorbing tape with an adhesive tape, coated on both sides, folded around one of the longitudinal edges of the first-mentioned tape to provide a composite sealing tape which in turn is folded over the edges of the glass panels, the 30 two tapes being adhesively joined and the composite tape adhering to the glass panels as well as to the grooved walls when the panels are in assembled position.

Other objects, novel aspects, advantages, and economies peculiar to the invention will become 35 apparent as the following description proceeds in view of the drawing, in which:

Fig. 1 is a perspective view of the improved display case structure;

Fig. 2 is an enlarged transverse section taken 40 in the direction of line 2—2 of Fig. 1;

Fig. 3 is an enlarged fragmentary perspective detail of the panel mounting means;

Fig. 4 is an enlarged fragmentary section taken 45 along line 4—4 of Fig. 2 through a corner of the case to illustrate the mounting of adjoining panels; while

Fig. 5 is a perspective detail of the composite sealing tape.

A preferred form of the invention is shown in 50 Fig. 1 and includes a pair of end frames 10 formed preferably by casting, the form of the frames in the present instance being substantially that of a trapezoid so that there are opposite parallel top and bottom rails 11 and 12 and opposite non- 55 parallel side bars 13 and 14.

The bottom rails 12 of the frames are preferably provided with a flared flange 15 (Figs. 2 and 3) which is adapted to slide into a groove or track (not shown) formed in the heads 16 on uprights 17. The uprights are adapted for mounting on the edge of a counter 18 and each have a lateral foot 19 resting on the top of the counter with portions projecting below the top (not seen) and attached in any suitable manner to the rear side of the counter, so that the uprights are rigidly 10 secured.

If desired, the case may be bodily slid from engagement with the uprights and fitted onto a relatively flat base member (not shown) having 15 spaced grooves to receive the tracks 15, so that the case may be mounted flush with the top of the counter.

The walls of the display case are formed by a plurality of glass panels 20 arranged substantially edge to edge with opposite endwise portions fitted 20 into the frames 10 in the manner hereinafter described.

An important feature of the panels 20 is the provision of enlarged bulb or beaded edges 21 along at least one of the lengthwise margins of each 25 panel. This bulb edge formation or beading constitutes a protective means insuring exposed edge portions against chipping and similar injury, and the panels are so mounted in forming the side walls of the case that the beaded edges are exposed and arranged to protect the unbeaded edges of adjoining panels.

Since the end of the case may or may not be arranged to permit viewing the interior thereof, ordinary glass panels 22 (Fig. 3 particularly) are 35 mounted in the open portions of the end frames 10, the latter being cast solid in the event that it is not necessary that the ends of the case be "open" or transparent.

The frame structures 10 are provided with communicating tracks or grooves 23 extending around the inner surface portions 24 of each frame member, the grooves 23 being adapted to receive the endwise edges of the glass panels constituting the main side walls of the case, as distinguished from 45 the end wall panels 22.

Each of the frame members 10, moreover, is provided with a ledge 25 around the inner margin of the opening thereof and into which the end panels 22 are fitted.

The several panels are securely sealed in their engagement with the several frame members and to this end a novel sealing means has been provided in the form of an elongated fabric tape 30 of a material, such as felt, which will act as a 55

sort of shock absorber. Folded over one of the long edges of the inner tape 30 is a second or adhesive tape 31 which is provided with an adhesive on both of its surfaces so that it will adhere 5 to the inner tape 30 and also present opposite adhesive surfaces on its outer sides. In this manner, there is formed what may be termed for convenience a composite adhesive sealing tape which is adapted to be folded around the edges of the 10 panels before they are inserted into their respective grooves.

In the illustration of Fig. 3, the composite tapes have their long edges 32 turned up to form channel-like strips, it being more convenient to 15 bring out the details of this arrangement in this manner, rather than by showing the tape already applied to the edge of the glass, as in the case of the panels 22, or as viewed in Fig. 4. It will be understood, of course, that the sealing tapes 32 20 may be formed up in substantially the channel shape shown in Fig. 3 prior to pressing the glass plates into their grooves, if this procedure should be preferred.

When the composite sealing tapes 32 have 25 been applied to the endwise edges of the main panels 20, the frame members 10 are pressed onto the respective ends of the panels, and the composite tape, of course, adheres to both the glass and the surface portions of the grooves, 30 the fit being made relatively tight with the result that the frame members are secured to the panels and hold the latter in assembled relation with sufficient firmness to permit handling of the case structure prior to mounting the same on the 35 counter.

The end wall plates 22 are also provided with sealing tapes 32, but as illustrated in Figs. 3 and 4 these latter plates are simply dropped into the inner frame portion of the end members, only 40 two of the three surfaces of the tapes 32 adhering to the confronting surfaces of the ledges 25. Further to secure the end panels in position there are provided small angles or cleats 34 screwed to the ledge portions 25 so as to bear against the 45 panels 22 and prevent withdrawal of the same from the ledge formations.

The main side wall panels 20, as heretofore mentioned, are so mounted in the frame members that the beading portions 21 of one panel 50 will overlie the edge portion 21a of the adjoining panel and protect this edge portion from glancing blows and other causes of injury.

A closure for the case may include a pair of end brackets 40 (Fig. 2) each having an elongated groove 41 and each pivotally secured as at 55 42 to a slightly enlarged upper corner portion 43 in each of the brackets 10, there being a closure panel 44, similar to the panels 20, fitted firmly in the groove portions between the members 40. Each of the bracket members is provided with a 60 handle portion 45 by means of which the door or closure may be raised into the dotted line position seen in Fig. 2.

It is important to observe that the lower edge portion 46 of the door panel is beaded and overlies a similarly beaded edge 21b of the bottom panel, with the result that the lower edge portion of the closure and the confronting edge portion of the bottom are insured against injury due to chipping as a result of manipulation of the 65 door and passing articles into and out of the case, this region being exposed to the greatest abuse in that respect.

The objects and advantages of the invention 70 may be accomplished by modifications in the 75 specifically described illustration without depart-

ing from the scope or spirit of the invention as the same is defined in the appended claims, all equivalent arrangements with respect to form, location, and operation of the parts being expressly included in said claims. 5

Having thus described my invention, what I claim as new and desire to protect by Letters Patent is:

1. A display case including a pair of oppositely positioned end members each having three angularly extended contiguous grooves corresponding to the three adjoining sides of a case structure, glass panels having opposite endwise edge portions each fitted into one of said grooves in the opposite end members whereby to define three 15 sides of said case, each of said panels having a beaded edge portion extended between said opposite end members thereof and positioned so as to overlie the confronting edge portion of an adjoining panel, and a fourth panel constituting 20 a closure for a fourth and remaining side of said case and mounted in bracket means in the form of a pair of rigid bands fitted around opposite end portions of the fourth panel and pivotally supported by said end members, said closure panel 25 having a beaded edge portion opposite its pivoted side and arranged to confront a similarly beaded edge formed on the confronting one of said three panels.

2. A display case including a pair of opposite 30 end frames, three elongated glass panels each having opposite end portions fitted into supporting engagement with one of said frames in such manner that said panels are disposed edge to edge to define the three sides of a casing enclosure, each of said panels having a longitudinal edge portion provided with an enlarged beading arranged to overlie the edge portion of the adjoining panel in protective relationship with the latter, the arrangement of such panels providing 35 a fourth and open side for said case, and a fourth elongated closure panel having opposite end portions each fitted into an elongated band-shaped bracket pivotally attached at one of its ends to one of said frame members, whereby to dispose 40 said panel in position to constitute a fourth side for said case, said brackets being pivotable to move said closure panel into and out of closing relationship with respect to said fourth open side, the edge portion of said closure panel opposite the side at which it is pivoted being provided with a beading disposed opposite a confronting free edge portion of one of said first- 45 mentioned panels which constitutes a bottom for the case. 50

3. In a display case, the combination with opposite end frames of glass panels arranged with longitudinally extensive edges overlapping corresponding edge portions of adjoining panels on three sides of a four-sided case structure, said end frames being provided with upper and lower horizontally extending grooves for receiving the top and bottom panels of the case and each being provided with a third groove in a side thereof communicating with the top and bottom grooves and into which the opposite end portions of one of the side forming panels is fitted in edgewise relationship with the other panels aforesaid, one of the longitudinal edge portions of each of said panels being bulbous and overlying a plain edge portion of an adjoining panel, said grooves being enlarged near one end so that the bulbous edge portions of the corresponding panels will fit snugly therein, said case being provided with a hinged fourth side including a glass panel having a bulbous edge and mounted in a pair of spaced 55 60 65 70 75 80 85 90 95 100

metal bands extending transversely around said panel and each pivotally mounted in said end frames beneath said top panel, said fourth panel having a bulbous edge portion opposite the pivotal mounting thereof adapted to confront the bulbous edge portion of the bottom panel, at least one of said bands being provided with a handle extension.

4. In a glass display case including opposite end frames supporting glass panels in positions

defining three of four sides of said case, means providing a hinged fourth side for said case and including a glass panel having a pair of rigid metal bands fitted around the same near opposite end portions thereof, each of said bands at one end being pivotally mounted in one of said end frames and at least one of said bands having a handle extension thereon in the region remote from the pivotal mounting thereof.

SAMUEL BLOOMFIELD. 10
